(57) **CLAIM**

The ornamental design for a cap for syringe, as shown and described.

DESCRIPTION

FIG. 1 is a front elevational view of a cap for syringe showing my new design;

FIG. 2 is a rear elevational view thereof;

FIG. 3 is a top plan view thereof; a bottom plan view thereof being a mirror image,

FIG. 4 is a cross-sectional view taken along the line 4-4 in FIG. 1 thereof;

FIG. 5 is a right side view thereof; and

FIG. 6 is a left side view thereof.

FIG. 7 is a right perspective view thereof;

FIG. 8 is a left perspective view thereof; and,

FIG. 9 is a referential cross-sectional view thereof in a using condition, wherein the cap is placed on a syringe tip.

The broken line in the drawings is included for the purpose of illustrating environment and forms no part of the claimed design.

1 Claim, 9 Drawing Sheets
